UNITED STATES PATENT OFFICE.

ARTHUR PAUL HORN, OF FORT THOMAS, KENTUCKY.

WATER-SHOE.

1,191,788.

Specification of Letters Patent. Patented July 18, 1916.

Application filed March 9, 1916. Serial No. 83,157.

To all whom it may concern:

Be it known that I, ARTHUR P. HORN, a citizen of the United States, residing at Fort Thomas, in the county of Campbell 5 and State of Kentucky, have invented certain new and useful Improvements in Water-Shoes; and I do hereby declare the following to be a full, clear, and exact description of the invention, such as will enable others skilled in the art to which it appertains to 10 make and use the same, reference being had to the accompanying drawings, and to the letters and figures of reference marked thereon, which form a part of this specification.

This invention relates to new and useful improvements in water shoes and it has for its object to provide a device of this character which, when not in use as a water shoe, 20 may be collapsed and folded to facilitate easy carrying of the same on land.

A further object of the invention is to provide water shoes of this form which may be inflated and used as a pneumatic matress for sleeping purposes when occasion 25 may require, and further to provide water shoes which, when inflated and secured to the feet of a wearer, will enable him to travel upon the surface of a body of water 30 with ease and safety.

The invention comprises various details of construction, combinations and arrangements of parts which will be hereinafter fully described, shown in the accompanying 35 drawings and then specifically defined in the appended claim.

My invention is illustrated in the accompanying drawings, in which:

Figure 1 is a top plan view of water shoe 40 constructed in accordance with my invention. Fig. 2 is a bottom plan thereof. Fig. 3 is a side elevation. Fig. 4 is a view showing the shoe in folded position, and Fig. 5 is a cross section taken on line 5-5 of Fig. 3. 45 Reference now being had to the details of the drawings by letter, A designates a water

shoe comprising a frame having three folding frame members A', A² and A³, suitably hinged together as at A⁴ and A⁵. The middle frame section A² has a shoe upper A⁶ 50 secured thereto and is adapted to receive and be secured to the foot of a wearer. Secured to the under side of said frame, as by cord or the like is a sack or inclosure B of flexible folding material. Said sack is adapted to 55 contain a pneumatic pouch B' which, when inflated, will support the wearer upon a body of water.

The rear end corners of the rear member A³ and the front corners of the front member A' are provided with clips or sockets A⁷ and A⁸, and between the downwardly extending portions of the clip A⁸ is pivotally mounted a feathering blade C which will swing up against the bottom of the sack 65 when the shoe is pushed forward and will project downward and serve as an abutment or anchorage while the other shoe of the wearer is being pushed forward.

By inserting rifle barrels or suitable sticks, 70 not shown, within the clips, the shoe may be used as a table should the occasion require. Suitable cords may be attached to the inner clips of each shoe to prevent the feet from becoming separated too far. 75

What I claim to be new is:—

A water shoe comprising a frame made up of sections adapted to fold one upon another, a shoe upper secured to the intermediate of the frame sections, a sack secured 80 to the sections of the frame and a pneumatic pouch secured to the sack, and clips secured to the outer end of one of said sections, and a feathering blade pivotally mounted between the insides of said clips. 85

In testimony whereof I hereunto affix my signature in presence of two witnesses.

ARTHUR PAUL HORN.

Witnesses:

E. JUST,

A. KUECHLER.
